UNITED STATES PATENT OFFICE.

ORIEN BYRON PICKERING, OF ENDICOTT, NEW YORK.

STAMP.

1,422,474.

Specification of Letters Patent. Patented July 11, 1922.

Application filed October 26, 1921. Serial No. 510,553.

To all whom it may concern:

Be it known that I, ORIEN BYRON PICKERING, a citizen of the United States, and a resident of Endicott, in the county of Broome and State of New York, have invented certain new and useful Improvements in Stamps, of which the following is a specification.

My invention relates to improvements in stamping machines of the type of construction in which a die carrying hammer is operatively supported in a desired position with respect to a work-supporting member, and it consists in the combinations, constructions and arrangements herein described and claimed.

An object of my invention is to provide a stamp of the character described, in which a die-carrying hammer is adjustably supported, whereby the device is suitable for use in stamping flat pieces of work, such as hides and pieces of leather, which vary in thickness.

A further object of my invention is to provide a device of the character described having means for stamping and counting pieces of work at the same operation.

A still further object of my invention is to provide a device of the character described in which the parts contacting the work are made of a non-ferrous material suitable to withstand the chemical action and the general wet nature of the work without deterioration.

A still further object of my invention is to provide a device of the character described that is simple in construction, not likely to get out of order easily, and thoroughly effective for the purpose intended.

Other objects and advantages will appear in the following specification and the novel features of the invention will be particularly pointed out in the appended claims.

My invention is illustrated in the accompanying drawings, forming a part of this application, in which:

Figure 1 is a perspective view of the device.

Figure 2 is an end view of the same, portions thereof being broken away and other portions being shown in section.

Figure 3 is a side elevation of the device.

Figures 4 and 5 are enlarged perspective views of elements embodied in the device, and

Figure 6 is a view similar to Figure 2 of a fragmentary portion of the mechanism shown in the latter.

In carrying out my invention, I provide a supporting frame which embodies inclined legs arranged in pairs 1-1 and 2-2. Corresponding legs of the pairs are joined at their upper ends by cross bars 3 and 4 respectively. The legs 2-2 are connected and held in spaced apart relation through the agency of an upper tie bar 5 and a lower tie bar 6, whereby the cross bars 3 and 4 will be held clamped against opposite faces of the web of an I-bar 7. The latter serves as an anvil for the device, as will presently appear.

A standard 8 is supported in upright position by means of brackets 9 and 10, which are shown as being attached to the lower and upper tie bars 6 and 5, respectively. The standard 8, which is shown as a channel iron, is formed with a vertically extending slot 11 therein beginning at about the level of the upper base of the anvil 7. The slot 11 opens through the sides of the standard 8, which sides extend at right angles to the anvil 7 and the slot is therefore parallel with the anvil 7.

A hammer adjustably supported on the standard 8 by means which will be herein-after described, comprises a die-carrying head 12 held on the outer end of a handle 13. The latter is arranged with its inner end held within the tubular arm 14 of a handle holder which also embodies a body portion 15 (see Fig. 5). It is to be observed that the tubular portion 14 of the holder is merged into the body portion 15 intermediate of the latter and that the holder is therefore substantially T-shaped. The body portion 15 of the holder is provided with an axial bore 16, in which is received a short shaft 17. The ends of the latter project into alined openings 18 and 19 in the arms 20 and 21 respectively of an adjustable bracket 22, which is slidably disposed on the slotted portion of the standard 8 and is maintained thereon for slidable movement by the engagement of the inturned extremities 23 and 24, respectively, of the arms 20 and 21 with the standard 8. It will thus be manifest

that the ends of the shaft 17 will extend through the slot 11 in the sides of the standard 8 before engaging the arms of the adjustable bracket 22, whereby the extent of 5 movement of the adjustable bracket 22 is limited to the length of the slot 11.

The handle holder is formed with an integral flange 25 which depends from the under side of the tubular portion 14 when 10 the holder is supported by the bracket 22, as illustrated. A link 26 is pivotally attached at its upper end to the flange 25 adjacent to the forward end of the latter and is pivotally attached at its lower end to a 15 treadle 27 intermediately of the latter. The treadle 27 is fulcrumed at one end, as at 28, on the standard 8. A retractile spring 29 attached at one end to the treadle 27 and at its other end to the standard 8 at a point 20 slightly below the lower end of the slot 11, as at 30, exerts a tension on the treadle 27 which tends to maintain it in the position illustrated in Figure 2.

A numbering or counting device, which 25 may be of any suitable known type of construction, is shown diagrammatically as being attached to the standard 8 at the upper end of the latter. In the drawings, I have indicated a numbering device in general, at 30 31. A lever and link arrangement indicated generally at 32 operatively connects the flange 25 of the handle holder with the numbering device 31.

From the foregoing description of the 35 various parts of the device, the operation thereof will be readily understood. The device is designed particularly for use in stamping and counting hides and pieces of leather in tanneries. In the form of the device illustrated, the head 12 is designed to carry two 40 separate dies, indicated at 33 and 34 respectively and a like number of face plates 35 are secured upon the upper face of the anvil 7 to receive the impact of a hammer blow. 45 The hammer head 12, the handle holder, and the adjustable bracket 22 are all formed of a non-ferrous material, which is suitable to withstand the action of the chemicals and other liquids with which articles of work of 50 the character described are impregnated. The face plates 35 are formed of copper or other relatively soft material so that the dies will not be injured in the event that the force of the blow is sufficient to force the 55 same completely through the work.

In service, an article to be stamped and counted, indicated at 36, is superposed on the face plates 35. Foot pressure upon the treadle 27 will then cause the hammer head 60 12 to be forced downwardly against the tension of the spring 29. The faces of the dies 33 and 34, bearing desired characters, not shown, will contact the portions of the article 36 superposed directly upon the face plates 35, whereby each of the dies will make 65

the desired impression on the work. Upon the downward stroke of the hammer, the lever and link mechanism, indicated at 32, will be actuated and the piece of work stamped will be counted through the agency 70 of the numbering mechanism 31. When the pressure upon the treadle 27 is removed, the action of the retractile spring 29 will occasion the return of both the treadle 27 and the hammer 12 to the positions illustrated 75 in Figure 2, the hammer moving from the position illustrated in Figure 6.

A recoil block 37 formed of rubber or a like resilient material is attached to the standard 8 by bolts 38 in position to receive 80 the impact of the hammer handle at the end of the return stroke of the latter.

The adjusting bracket may be moved vertically along the standard 8 between the limits of the slot 11 and secured in adjusted 85 position through the agency of set screws 39. It will therefore be manifest that the hammer embodied in the device and described herein may be adjusted vertically so that the faces of the dies will contact 90 the surfaces of pieces of work of different thicknesses uniformly and evenly. In other words the faces of the dies 33 and 34 will be parallel with the faces of the face plates 35 when the hammer is at the end of its 95 down stroke.

I claim:

1. A device of the character described comprising a vertical standard having a vertically extending slot formed therethrough, 100 a hammer comprising a handle and a head secured on the handle at one end thereof, said head being adapted to hold a die in such manner that the face of the die will be disposed in a horizontal plane when the handle is horizontal, a holder receiving the other end of said handle, a bracket having arms straddling the slotted portion of the standard and being movable vertically on the standard, means engaging the said holder, the said slot of the standard, and the said arm of the bracket for pivotally attaching the hammer to the said bracket and for guiding the bracket in its vertical movement, whereby the bracket may be adjusted 110 to permit of the hammer handle occupying different horizontal planes when in dropped position, and an anvil having a face lying in a horizontal plane and in position to receive the impact of a die carried by the said hammer head. 115

2. In combination, a vertical standard of channel formation and having registering vertically extending slots formed through the sides thereof, a hammer having a handle 125 and a head adapted to hold a die in such manner that the face of the die will be disposed in a horizontal plane when the handle is horizontal, a substantially T-shaped holder having a body provided with an axial 130

- bore and a tubular portion extending at right angles from the body intermediately of the latter, said tubular portion receiving the end of the hammer handle remote from the head, a substantially U-shaped bracket slidably embracing the standard and having openings through its sides in registry with each other and with the slots of the standard, a shaft projected through the said registering openings and slots, whereby the holder is supported on the standard in such manner as to permit of limited movements thereof vertically, means for releasably locking the bracket to the standard in desired vertically adjusted positions, and an anvil having a face lying in a horizontal plane and in position to receive the impact of a die carried by the said hammer head.
3. In a device of the character described, a support having a guide slot formed therethrough, a bracket slidably embracing the slotted portion of the support, means carried by said bracket and engaging the guide slot to limit the movements of the bracket along said support, and means swingingly supported upon said bracket for holding a die.
4. In a device of the character described, an elongated support, a bracket slidably embracing the support, means carried by the bracket for releasably locking the latter to

the support in desired positions therealong, and a hammer pivotally supported upon said bracket, said hammer having a head adapted to hold a die.

5. In a device of the character described, an elongated support having a vertical guide slot formed therein, a bracket slidably embracing the slotted portion of the support, means for releasably locking the bracket to the support in adjusted positions therealong, a hammer comprising a handle and a head secured on the handle at one end thereof, said head being adapted to hold a die, a holder receiving said handle, and means adjacent the said holder, the slot of the support, and the bracket for pivotally attaching the holder to the bracket and for guiding the bracket in its movements along the support.

6. In a device of the character described, a vertical standard, a bracket slidably engaging the standard, means for releasably locking the bracket to the standard in adjusted positions therealong, a holder pivotally supported upon said bracket and having a tubular portion extending laterally thereof, and a hammer having a handle held at one end in the tubular portion of said holder and being provided at its other end with a head adapted to hold a die.

ORIEN BYRON PICKERING.
